UNITED STATES PATENT OFFICE.

EDWIN E. PETTIBONE AND ROSE A. LENZ, OF CLEVELAND, OHIO.

COPY-HOLDER.

1,293,905.

Specification of Letters Patent. Patented Feb. 11, 1919.

Application filed April 29, 1918. Serial No. 231,341.

To all whom it may concern:

Be it known that we, EDWIN E. PETTIBONE and ROSE A. LENZ, citizens of the United States, and residents of Cleveland, county of 5 Cuyahoga, and State of Ohio, have jointly invented a new and useful Improvement in Copy-Holders, of which the following is a specification, the principle of the invention being herein explained and the best mode 10 in which we have contemplated applying that principle, so as to distinguish it from other inventions.

The present invention relates to devices for positioning and holding bunches of 15 loosely bound copy and the like. Provision is made for holding both the sheets to be copied and the copied sheets and for so holding the same that there is no danger of injuring or tearing the sheets. Another 20 object is the provision of a guide plate which is not in actual contact with the paper and for providing means whereby the copy may be split up so that a part only may be used, the rest being securely held with no opportunity 25 of its becoming mixed with the sheets already copied. To the accomplishment of the foregoing and related ends, said invention, then, consists of the means hereinafter fully described and particularly pointed out 30 in the claims.

The annexed drawings and the following description set forth in detail certain mechanism embodying the invention, such disclosed means constituting, however, but one 35 of various mechanical forms in which the principle of the invention may be used.

In said annexed drawings:—

Figure 1 is a top plan view of our improved copy-holder; Fig. 2 is a front elevation; Fig. 3 is a side elevation; Fig. 4 is a section on line 4—4, Fig. 3; Fig. 5 is a section on line 5—5, Fig. 1; Fig. 6 is a detail of a modification of a pressure finger; and Fig. 7 is a detail of another modified 45 form of pressure finger.

The holder consists of a suitable base 1 provided at the forward ends with adjustable legs 2 having slots 3 therein mounted on screws or pins 4 provided with nuts 5 to secure them in their adjusted positions, as shown in dotted line in Fig. 1 and Fig. 3. When not in use they will preferably be retained in the position shown in full lines in the same figures. The base as shown 55 consists of two side members 6 connected by

cross members 7, although any suitable base may be used.

Mounted on the base 1 by means of screws 8 or the like are two frame members 9 which are connected by a series of rods or bars 60 10, 11, 12, 13 and 14, which are non-rotatably mounted parallel to each other in the frame members to form a rigid frame for the device.

The rods 11 and 12 are connected by a 65 guard 15 composed of a series of spaced guard sheets of metal or the like attached to the rods and presenting a smooth forward surface. Below the rod 12, a shaft 16 is rotatably mounted in the members 9 and provided at its outer ends with operating wheels 70 17 having knurled or roughened surfaces. Mounted on this shaft and rotatable therewith are a series of spaced rollers 19 adapted to extend through the spaces between the 75 guard sheets. As illustrated, there are four such rollers shown, but the number is optional and may be changed according to the width of the device and the various uses for which it may be designed. Loosely mounted 80 on the rod 10 is a guide plate 20 provided with an extending finger 21 for moving the plate about the rod. At each end of the rod a coil spring 22 is mounted, having one end extending downwardly and in contact with 85 the rod 11, while the other end extends upwardly and engages in a slot 23 formed in one end of a yoke 24 loosely mounted on the rod 10. The rod passes through apertures 90 in the yoke 24 which has a finger 25 at its inner end extending upwardly and adapted 95 to engage a hook member 26 which engages at its ends with two pressure fingers 27. These fingers have apertured bosses 28 through which the rod 10 extends and are held in clips 29 formed on the under side of the plate 20. The hook member 26 is fastened over pins in the sides of the fingers and the pressure of the finger 25 against the hook keeps them in their lower position 100 against the rollers 19. The pressure fingers have a limited amount of movement between the clips and the plate 20 and are provided with rolls 30 adapted to contact with and be rotated by the knurled rollers on the shaft 105 16. Each roll 30 is thus caused to exert pressure against its opposed roller 19 when paper of varying thickness or creased surface is passed between them.

In Figs. 6 and 7 two modified forms of 110

pressure fingers are shown, the finger 35 shown in Fig. 6 being similar to the one previously described except that only one such finger is used and the finger proper has a stud 36 engaged by the end of a spring 37 and being held in a clip 38 formed on the under side of the plate.

The other form shown in Fig. 7 shows a pressure finger 39 provided with the usual 10 roll 30 mounted on a flat spring 31 attached to the plate and adapted to bear against one of the knurled rollers.

By the use of the pressure fingers mounted below the guide plate, and capable of limited 15 movement independent thereof, and independent of each other, the sheets of paper will be held firmly between the rolls on the pressure fingers and the knurled rollers on the shaft and will not be in contact with the 20 guide plate so that when the shaft 16 is rotated, the papers will be moved without deviation, and as the plate does not contact, then there is no danger of tearing or injuring the sheets.

25 To the rear of the shaft 16 are mounted two uprights 40 upon which is mounted an inclined plate 41 held in position on pins 42 passing through the uprights. The plate 41 has a series of spring clips 43 mounted 30 thereon adapted to hold a data guide 44 or the like so that the operator may always have a heading in sight.

In front of the rod 13 two stub rods 45 are mounted in the frame members and 35 have coil springs 46 mounted thereon, the outer ends of such springs being held under stud 47 on the frame members and the inner ends engaging in slots 49 in small studs 50 carried by the clip 51 which has two bosses 40 52 apertured to receive the stub rods 45. The clip is thus held against the rod 13 by the action of the springs and is provided with fingers 53 for lifting it to insert or withdraw the paper.

45 In the rear of the holder and in the upwardly extending ends of the frame members the last rod 14 is mounted. A clip 54 similar to clip 51 is employed with this rod, the clip being mounted on stud rods 55 and 50 using spring 56 to operate it in the manner described for clip 51.

In using the device, the intermediate clip 51 is used only when the bunch of papers is 55 too thick to be used at one time between the rollers. When used, it is employed as shown in Fig. 3, the clip 51 being employed to hold the sheets 60 not in use while those sheets 61 being copied are mounted between the rolls and below the guide plate which is 60 used as a line guide. The clip 54 at the rear is used to hold the sheets 62 as they are finished and pulled out of the first clip, as will be clearly seen from Fig. 3.

The use of the rollers which are capable 65 of limited movement with respect to the

guide plate allows the plate to be close to the sheet being copied, so as to furnish a satisfactory line guide but without the plate exerting any pressure against the sheet which might cause tearing or injury when 70 the sheet is moved. Besides this the pack or bunch of papers may be split up and yet they cannot become mixed as the part still to be copied is held in a separate clip from the copied sheets.

75 A copy holder of sufficient width to accommodate standard legal size paper will handle any lesser width down to a newspaper clipping. The use of pressure fingers having independent adjustment moves the 80 sheets uniformly through the holder as the sheets are gripped evenly and securely by the rolls. The holder handles thick cards or thin sheets without difficulty and the length of the sheet is immaterial. By movement of one hand one or more lines may be quickly brought into view and where the copy is in columns the use of the data guide keeps the correct heading for each column always in view.

90 Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a copy-holder, the combination of a 100 frame, a shaft rotatably mounted therein and provided with knurled rollers, a pivotally mounted guide plate in front of said rollers, pivotally mounted pressure fingers pivotally mounted with said guide plate and movable therewith, said fingers being capable of limited independent movement and being adapted to press the copy against said knurled rollers.

2. In a copy-holder, the combination of a 110 frame, a shaft rotatably mounted therein and provided with knurled rollers, a pivotally mounted guide plate in front of said rollers, pressure fingers pivotally mounted with said guide plate and movable therewith and having slight independent movement, rolls mounted in said fingers, alined with said rollers and adapted to hold the sheet firmly between the same, and resilient means for holding such pressure fingers and 120 rolls against said rollers.

3. In a copyholder, the combination of a frame, a shaft rotatably mounted therein and provided with knurled rollers, a pivotally mounted guide plate in front of said 125 rollers, pivotally mounted pressure fingers pivotally mounted with said guide plate and movable therewith and having slight independent movement, rolls mounted in said fingers, alined with said rollers and 130

adapted to hold the sheet firmly between the same, and springs mounted on said shaft and adapted to maintain said rolls in contact with said rollers.

- 5 4. In a copyholder, the combination of a frame, a shaft rotatably mounted therein and provided with knurled rollers, a pivotally mounted guide plate in front of said rollers, pressure fingers pivotally mounted
 10 about the same axis as said guide plate and having lost motion connection therewith, rolls mounted in said fingers and coöperating with said rollers to hold said copy therebetween, and resilient means normally holding
 15 said fingers in their operative position.
5. In a copyholder, the combination of a frame, a shaft rotatably mounted therein and provided with knurled rollers, a pivotally mounted guide plate in front of said
 20 rollers, pressure fingers pivotally mounted about the same axis as said guide plate and having lost motion connection therewith, rolls mounted in said fingers and coöperating with said rollers to hold said copy there-
 25 between, and a spring adapted to normally press said fingers and rolls into engagement with said rollers.

6. In a copy-holder, the combination with
 a frame, of means for holding and moving
 30 such copy consisting of coöperating rollers and a guide plate, a clip at the rear of the

machine for holding the used copy and an intermediate clip adapted to hold copy.

7. In a copy-holder, the combination with a frame, of means for holding and moving 35 such copy consisting of coöperating rollers and a guide plate, a data guide mounted adjacent to such rollers and adapted to carry a heading, and two clips at the rear of the holder to retain the unused and the used 40 copy respectively.

8. In a copy-holder, the combination with a frame, of means for holding and moving such copy consisting of coöperating rollers and a guide plate, a data guide mounted adjacent to such rollers and provided with 45 spring clips to hold heading data, and two clips in the rear part of the holder adapted to retain the used and unused copy respectively. 50

9. In a copy-holder, the combination with a frame, of means for holding and moving such copy consisting of coöperating rollers and a guide plate, a data guide mounted adjacent to such rollers and provided with 55 spring clips to hold heading data and two spring actuated clips on the rear part of the holder adapted to hold the used and unused copy respectively.

Signed by us, this 26th day of April, 1918. 60

EDWIN E. PETTIBONE.
 ROSE A. LENZ.
